United States Patent Office

Des. 212,561
Patented Oct. 29, 1968

212,561

MICROFILM READER OR SIMILAR ARTICLE

Lewis E. Simpson, 255 W. 234th St., Wilmington, Calif.
90744, and William E. Karow, 7367 W. 93rd Place, Los
Angeles, Calif. 90045

Filed Apr. 11, 1967, Ser. No. 6,646

Term of patent 14 years

(Cl. D61—1)

Fig. 1

Fig. 2

Fig. 3

FIGURE 1 is a front, top and right side perspective view of a microfilm reader or similar article, showing our new design;

FIGURE 2 is a left side elevational view, the right side being substantially a mirror image thereof; and

FIGURE 3 is a rear elevational view thereof.

A portion of FIGURE 1 is diagonally lined to indicate translucency.

We claim:

The ornamental design for a microfilm reader or similar article, as shown and described.
